UNITED STATES PATENT OFFICE.

EDMOND ARMANT, OF BINGHAMTON, NEW YORK.

DESIGN FOR A SACHET OR PERFUME CONTAINER.

No. 39,854.

Specification for Design.

Patented March 2, 1909.

Application filed October 12, 1908. Serial No. 457,448. Term of patent 7 years.

To all whom it may concern:

Be it known that I, EDMOND ARMANT, a citizen of the United States, residing at the city of Binghamton, in the county of Broome and State of New York, have invented a new, original, and ornamental Design for a Sachet or Perfume Container, of which the following is a specification, reference being had to the accompanying drawing, forming part thereof.

The figure is a plan view of a perfume or sachet container showing my new design.

I claim:

The ornamental design for a sachet or perfume container as shown.

EDMOND ARMANT.
